CLAIM

The ornamental design for an air freshener, as shown and described.

DESCRIPTION

FIG. 1 is a perspective view of a first embodiment of an air freshener in a first, exploded position according to the present invention;

FIG. 2 is a perspective view of the air freshener of FIG. 1 in a second position according to the present invention;

FIG. 3 is a front view of the air freshener according to the present invention;

FIG. 4 is a rear view of the air freshener according to the present invention;

FIG. 5 is a left side view of the air freshener according to the present invention;

FIG. 6 is a right side view of the air freshener according to the present invention;

FIG. 7 is a top view of the air freshener according to the present invention;

FIG. 8 is a bottom view of the air freshener according to the present invention;

FIG. 9 is a perspective view of a second embodiment of an air freshener according to the present invention;

FIG. 10 is a front view of the air freshener according to the present invention;

FIG. 11 is a rear view of the air freshener according to the present invention;

FIG. 12 is a left side view of the air freshener according to the present invention;

FIG. 13 is a right side view of the air freshener according to the present invention;

FIG. 14 is a top view of the air freshener according to the present invention; and,

FIG. 15 is a bottom view of the air freshener according to the present invention.

The broken lines shown in the drawings are for illustrative purposes only and form no part of the claimed design.
